UNITED STATES PATENT OFFICE

CHARLES E. GAHAGAN, OF PITTSBURGH, PENNSYLVANIA

BLADE HOLDER

Application filed May 14, 1928. Serial No. 277,695.

This invention relates to improvements in blade holders embodying among other characteristics a spring element.

Another object of the invention contemplated is a release member for the spring element.

A further object of the invention comprehends gripping elements adapted to retain the blade in position for use.

More specifically stated the holder consists of a handle member adapted to carry the spring element, gripping element and release member.

With the above and other objects in view, the invention further consists of the following novel features and details of construction, to be hereinafter more fully described, illustrated in the accompanying drawing and pointed out in the appended claim.

In the drawing:—

Figures 1 and 2 are reverse elevations of the invention.

Figure 3 is a longitudinal sectional view taken therethrough.

Figure 4 is a horizontal sectional view taken on line 4—4 of Figure 1.

Figure 5 is a fragmentary perspective end view of the holder.

Figure 6 is a perspective view of the spring element carrying the gripping elements and release member.

Referring to the drawing in detail, where-in like characters of reference denote corresponding parts, the reference character 10 indicates a handle member having a head 11 suitably enlarged and disposed at a slight inclination upon the end of the handle, the purpose of which will be presently apparent.

Said head is longitudinally split, as at 12, to provide sections 13 and 14. The slot 12 is adapted to accommodate a razor blade 15, preferably one such as the Gillette having two or more holes. The sections 13 and 14 are furthermore provided with registering openings 16, which are adapted to coincide with the openings in the blade 15.

A spring element 17, carried upon one side of the handle member 10 and the section 14, is provided with spaced parallel arms 18 and 19 disposed at right-angles thereto.

Gripping elements 20, projected from the arms 18 and 19, are adapted for reception within the openings 16 in the sections 13 and 14 and the adjacent openings in the blade 15. The spring element 17 is furthermore provided with openings 21 adapted to accommodate rivets or other fastening elements, such as indicated at 22 carried by the handle member 10, whereby the outermost end thereof carrying the arms 18 and 19 will be flexed, sprung or otherwise induced toward the outer surface of the section 14.

The section 13 is provided with a countersunk opening 23 adapted to receive a headed stud or release member, such as indicated at 24, and which is adapted for connection at its opposite end with the free portion of the spring element 17 to facilitate removal and replacement or interchanging of the blade 15.

Inasmuch as the head proper is disposed at an inclination, the blade may be used for cutting or scraping at angles which could not ordinarily be accomplished with a head disposed in the same plane with the longitudinal center of the handle.

As manifest from the illustration of the invention in Figure 4 of the drawing, wherein a horizontal sectional view through the sections 13 and 14 is illustrated, it is apparent that the outer sides of the sections 13 and 14 are beveled from the back of the head toward the entrance opening or slot for the blade 15, whereby the device may be effectively employed, as a scraper upon flat surfaces and the depth of the scrape or cut may be effectively regulated.

Furthermore the blade when worn or caked with scrapings may be readily discharged by depressing action exercised upon the headed stud 24. The blade will in and of itself drop from the head.

Inasmuch as I have described the invention as being primarily adapted for use as a scraper, it is obviously understood that the same could be effectively employed for use in the holding and stropping of razor blades.

Furthermore the outer ends of the gripping elements 20 may be serrated or otherwise roughened to facilitate frictional en-

gagement and retention of Gem and other backed blades.

As understood from the illustrations of the invention in Figures 1 and 2 of the drawings, it is to be noted that the back of the head is free, whereby the thumbs of the user's hands may be effectively employed to push the blade 15 in the event enough force or stress can not be exercised from the outermost end of the handle 10.

The invention is susceptible of various changes in its form, proportions and minor details of construction, and the right is herein reserved to make such changes as properly fall within the scope of the appended claim.

Having thus described the invention, what is claimed is:—

A blade holder comprising a handle having a split head upon one end, a blade fitted within the split of the head, a spring element mounted upon one side of the handle and head, gripping elements included upon the spring element and projecting through the head and engageable with the blade to retain same in position for use, and a release member having connection with the spring element and disposed upon the opposite side of the head to relinquish engagement of the gripping elements from the blade.

30. In testimony whereof I affix my signature.

CHARLES E. GAHAGAN.
